UNITED STATES PATENT OFFICE.

LOUIS GOHLKE, OF GRAND RAPIDS, MICHIGAN, AND FREDERICK H. MARX,
OF CHICAGO, ILLINOIS.

DESIGN FOR A TOY WHISTLE.

SPECIFICATION forming part of Design No. 25,470, dated May 12, 1896.

Application filed March 7, 1896. Serial No. 582,272. Term of patent 31 years.

To all whom it may concern:

Be it known that we, LOUIS GOHLKE, residing at Grand Rapids, in the State of Michigan, and FREDERICK H. MARX, residing at Chicago, in the State of Illinois, citizens of the United States, have invented and produced a new and useful Design for Toy Whistles, of which the following is a specification, reference being had to the accompanying drawing, which illustrates our design.

The leading feature of our design consists in the representation of the figure of a child sitting astride of a whistle and holding a wind-wheel. The child is shown with out-

stretched arms, the wind-wheel being held 15 between the hands. The outer or right-hand end of the whistle is shown as formed in the shape of a woman's head and bust.

What we claim as our invention, and desire to secure by Letters Patent, is-- 20

The design for a toy whistle, substantially as shown and described.

LOUIS GOHLKE,
FREDERICK H. MARX.
